UNITED STATES PATENT OFFICE.

JOHN D. CRAWFORD, OF CAMLACHIE, ONTARIO, CANADA.

PULLEY-RIM.

1,100,541.

Specification of Letters Patent. Patented June 16, 1914.

Application filed June 10, 1913. Serial No. 772,883.

To all whom it may concern:

Be it known that I, JOHN D. CRAWFORD, a citizen of Canada, residing at Camlachie, in the Province of Ontario and Dominion of Canada, have invented new and useful Improvements in Pulley-Rims, of which the following is a specification.

This invention relates to an extension rim which is adapted to be applied to the rim 10 of a small pulley in order to increase the diameter of its effective outer periphery, and has for an object to provide a device of this character which may be applied readily to the rim of a pulley without detaching the same from the shaft upon which it may be mounted, and which embodies adjustable means for rigidly securing the extension rim in position upon the pulley so that danger of slipping is obviated.

20 A further object of the invention is to provide an extension rim of the class described which includes a plurality of segments adapted to be arranged together so as to encompass the rim of the pulley to be built up, and adjustable means for clamping the said segments together upon the pulley rim.

A still further object is the provision of an extension rim of the construction just 30 described, wherein the adjustable clamping means for the rim segments is readily accessible for the purpose of adjustment.

The invention consists in the features of construction, combination and arrangement 35 of parts, hereinafter fully described and claimed, reference being had to the accompanying drawing in which:

Figure 1 is a side elevation of a pulley wheel, showing the rim applied thereto; 40 Fig. 2 is a top plan view of the same; Fig. 3 is a vertical sectional view taken on line 3—3 of Fig. 2; and Fig. 4 is a horizontal sectional view on line 4—4 of Fig. 1.

In the drawing, the numeral 1 designates 45 the extension rim which is adapted to be mounted upon the outer periphery of a small pulley wheel 2 so as to increase the size of the same. This rim is comprised primarily of two coacting sections 3 and 4, 50 which, as shown are semi-circumferential and have their ends meeting. Each rim section is composed of a plurality of abutting segments 5 which are constructed preferably of wood or of some similar material,

and which are provided with alining openings 6 adjacent to the ends thereof for the reception of the semi-circumferentially extending clamping rods 7. The extremities of these rods project past the ends of each rim section and are connected with adjustable clamping devices which will be presently described.

At each joint between the rim sections, a pair of binding segments 8 and 9 is provided. The meeting faces of these segments 65 contact evenly with each other as at 10, but the opposite faces thereof are provided with cut away portions 11 and 12, which are arranged in staggered relation to each other and leave the sustaining abutments 13 70 and 14 which engage the adjacent end segments 15 and 16 of the respective rim sections. The abutments 13 and 14 of one binding segment are thus disposed directly opposite to the cut away portions or access 75 spaces 12 and 11 respectively provided in the coacting binding segments. The rod openings 6 in the segments of one of the rim sections are disposed in staggered relation to the openings in the segments of 80 the coacting section, so that the openings in the segments of one section are in direct alinement with the openings 17 and 18 provided in the adjacent binding segment 8 and the openings 19 and 20 in the binding 85 segment 9 at one of the joints between sections. The binding segment openings 17 and 19 at this joint extend through the abutment 14 in the segment 8 and into communication with the cut away portion 11 of the 90 segment 9, and the openings 18 and 20 extend through the abutment 13 on the segment 8 and into communication with the cut away portion 12 of the segment 9 respectively. The corresponding extremities 95 of the clamping bolts 7 passing through this particular rim section project through the openings in the binding segments and the respective cut away portions in the segment 9 into the auxiliary openings 21 provided in the end segment of the other rim section, which is disposed in contact with the abutments of the binding segment 9. Clamping nuts 22 are adjustably mounted 100 upon these rod extremities which are externally threaded as at 23, and are disposed within the cut away portions of the segment 9, wherein they are accessible to a 105

wrench or other turning tool by which they may be adjusted so that each segment 9 will bind the adjacent segment 8 against the corresponding end of the particular rim 5 section referred to.

The rod openings provided in the other rim section are disposed in direct alinement with the openings 24 and 25 provided in the binding segment 9 at each joint and with the 10 openings 26 and 27 respectively in the co-acting binding segment 8. These openings in the binding segments extend through the corresponding abutments of the segment 9 and communicate with the adjacent cut 15 away portions of the segment 8 and are in alinement with the auxiliary openings 28 provided in the end segment of the rim section, previously dealt with, in engagement with the abutments of the segment 8. The 20 extremities of the binding rods 7 projecting through these openings are threaded as at 29 for the reception of the clamping nuts 30 adjustably mounted thereon and engaged with the binding segment 8 within its 25 cut away portions.

From the foregoing description it will be seen that the rim sections are provided with interlocking clamping means, whereby the segments of each section will be bound together securely and the sections themselves will be firmly united upon the pulley to be built up, when the clamping nuts, just described, are tightened. When these clamping nuts are loosened upon their respective 35 bolt ends, the rim sections and their segments will be loosened so that the rim may be removed readily from the small pulley by longitudinal movement, when the said pulley is mounted upon the free end of a 40 shaft. When this is not the case, the clamping nuts may be adjusted so as to work off the ends of the clamping bolts at one joint between the rim sections thereby opening this joint and permitting the removal of the 45 extension rim by lateral movement.

Extension rims constructed in accordance with the invention, may be produced in various sizes so that a rim may be procured for use in building up any pulley of a given

diameter to produce a larger pulley of a pre- 50 determined diameter.

Having thus described my invention, what I claim is:

1. An extension rim for pulleys comprising a plurality of semi-circumferentially extending sections adapted to have their ends disposed in spaced relation to each other, clamping rods projecting from the ends of the said sections, a pair of binding segments disposed between the adjacent ends of the 60 sections and provided with openings receiving the said rods, and an adjustable nut threaded onto each end of each rod and engageable with one of the binding segments of each pair on the face thereof opposite to 65 the coacting binding segment, each of said binding segments being provided in its face opposite to the coacting segment with a recess opening through an outer face thereof for the reception of the corresponding binding nut.

2. An extension rim for pulleys comprising a plurality of semi-circumferential sections adapted to have their ends disposed in spaced relation to each other, each of the 75 said sections being provided with axially spaced openings extending longitudinally therethrough, the openings of one section being positioned so as to be staggered with relation to the openings of the coacting section when the sections are assembled, clamping rods extending through the openings of each section and projecting therefrom, a pair of binding segments disposed between adjacent ends of the said sections and being 80 provided with openings through which the rods of both sections extend, and clamping nuts threaded onto the ends of the said rods and being adapted to bind the binding segment at the end of one section between the 85 said end and the coacting binding segment.

In testimony whereof I affix my signature in presence of two witnesses.

JOHN D. CRAWFORD.
